EMBOSSING TAPE MAGAZINE

Benedict E. Bogeaus, Los Angeles, Calif.
(333 N. Foothill Road, Beverly Hills, Calif.)

Filed Jan. 31, 1963, Ser. No. 73,384

Term of patent 14 years

(Cl. D74—1)

FIG. 1.

FIG. 2.

FIG. 3.

FIG. 4.

FIG. 5.

FIG. 6.

FIG. 8.

FIG. 9.

FIG. 1 is a perspective view of an embossing tape magazine showing my new design;

FIG. 2 is another perspective view thereof turned at an angle of 180°;

FIG. 3 is a front elevational view;

FIG. 4 is a right side elevational view;

FIG. 5 is a rear elevational view;

FIG. 6 is a top plan view;

FIG. 7 is a bottom plan view;

FIG. 8 is a left side elevational view in inverted position; and

FIG. 9 is a sectional view thereof taken on line 9—9 of FIG. 7.

I claim:

The ornamental design for an embossing tape magazine, substantially as shown and described.
